CLAIM

The ornamental design for a wine glass stem, as shown and described.

DESCRIPTION

FIG. 1 is a top perspective view of a wine glass stem in accordance with the present invention;

FIG. 2 is a side elevational view thereof, with the opposite side view being identical;

FIG. 3 is a front view thereof, with the rear view being identical;

FIG. 4 is a bottom perspective view thereof;

FIG. 5 is a top view thereof; and,

FIG. 6 is a bottom view thereof.

The broken lines in FIGS. 1-6 illustrating the glass and the foot are for environmental purposes only and form no part of the claimed design.

1 Claim, 6 Drawing Sheets
